Primary Examiner — Samantha Q Lawrence(74) *Attorney, Agent, or Firm* — Parker Poe Adams & Bernstein LLP(57) **CLAIM**

The ornamental design for a dress post base, as shown and described.

DESCRIPTION

FIG. 1 is upper perspective view of the present invention; FIG. 2 is a front, side perspective view thereof;

FIG. 3 is a top plan view thereof;

FIG. 4 is a bottom plan view thereof;

FIG. 5 is a front elevation view thereof;

FIG. 6 is a left side elevation view thereof;

FIG. 7 is a right side elevation view thereof; and,

FIG. 8 is a back side elevation view thereof.

The broken lines of FIGS. 1 and 2 show portions of the dress post base that form no part of the claimed design.

1 Claim, 8 Drawing Sheets(56)
